CHARGING MACHINE

Application filed September 23, 1931. Serial No. 564,690.

Our present invention relates to certain new and useful improvements in mechanism for charging molten metal into the flask or flasks of a centrifugal casting machine or machines of the type wherein the flask is provided with a refractory, such as a rammed sand lining.

The charging mechanism of the present invention is adapted more especially for use in connection with centrifugal casting machines for casting pipes of large diameter as, for instance, a diameter of 14 inches and larger, and a length of 16 feet more or less, and wherein a relatively large amount of metal is employed in each casting operation.

In machines of this type it is desirable to begin the charging of the flask at a point intermediate its ends and to then gradually discharge the metal lengthwise of the flask in order to insure an even distribution of the metal throughout the length of the flask, it being understood that distribution is also effected by the rotation of the flask in the casting operation.

An object of the invention is to provide a motor operated tilting ladle associated with a charging spout or trough, and with remote control means for tilting the ladle.

A further object of the invention is to provide a charging means for centrifugal casting machines wherein the ladle for the molten metal is mounted upon a travelling carriage provided with a spout or charging trough adapted to be introduced into and withdrawn from the flask of a centrifugal casting machine.

A still further object of the invention is to provide a novel construction and arrangement of motor operated means for tilting the ladle of a charging mechanism for a centrifugal casting machine.

To these and other ends the invention comprises the features of construction and combinations and arrangement of the various parts as hereinafter described and then more particularly pointed out in the appended claims. In order to enable others skilled in the art to understand, build and use our said invention, we will now proceed to describe the same in detail, reference be-

ing had for this purpose to the accompanying drawings, wherein,

Fig. 1 is a side elevation of a charging mechanism constructed in accordance with our invention and shown associated with a portion of a centrifugal casting machine and its flask;

Fig. 2 is a side elevation on a larger scale of a portion of the pouring ladle and its operating mechanism, the ladle being shown in fully tilted position;

Fig. 3 is a plan view of the charging mechanism; and

Fig. 4 is a front elevation of the charging mechanism.

Fig. 5 is a detail plan view, partly in section, showing the lost-motion connection between the speed-reducer crank and the link operated thereby.

In Fig. 1 we have shown the charging mechanism in association with a centrifugal casting machine, the flask of which is indicated by the reference letter A, the bell end of the flask being shown in this figure.

The charging mechanism is mounted upon a carriage 1, supported upon wheels 2, travelling upon tracks 3, the tracks being located in front of and in line with the flask A.

The tracks 3 are provided at their front ends with stops or bumpers 4, for a purpose presently to appear. Other track sections 5 are arranged in line with tracks 3, the track sections 5 being mounted upon the platform of a weighing scales mounted above the pit 6, the said track sections being provided at their rear ends with stops or bumpers 7.

The carriage 1 is driven by an electric motor 8, through speed reducing gearing 9, of any approved construction, which drives sprocket chain 10 passing around the sprocket wheel 12 attached to the front shaft 13 on which the front wheels 2 of the car are supported. The electric motor 8 is preferably controlled by a switch located at a remote point or control station.

The reference numeral 14 designates a U-shaped pouring spout or trough having an outlet 15 at its front end by means of

which molten metal poured into the trough may be introduced into the flask A, as presently to be described. The trough 14 is supported intermediate its ends by means of a yoke 16, the yoke and its trough being in turn held in position by means of opposed screws 17, each mounted in a bracket 18, supported upon the forward end of the carriage 1. The rear end of the trough pins 14', projecting from its opposite sides and which seat in notches formed in the lower end of angle-iron uprights 20, as more clearly shown in Fig. 2. A removable and replaceable filler block 18', Fig. 4, is arranged beneath the yoke 16, to permit vertical adjustment of the trough. By the arrangement shown the trough may be adjusted vertically as well as angularly in a vertical direction to bring its discharge end 15 in proper relationship with the interior of the flask to be charged. A hopper 19 having lateral trunnions 20' is supported in seats at the upper end of brackets 20 rising from the carriage 1, the hopper having a 25 spout 19' which discharges into the open trough 14. The reference numeral 21 indicates a ladle having a pouring lip 22 which discharges into the hopper 19 when the ladle is tilted and from this, into the 30 trough 14. The forward end of the hopper has lateral projections 19'' which rest upon the upper edges of the trough 14 as shown in Fig. 3.

The ladle 21 is supported by brackets 23, 35 secured to an oscillating shaft 24, mounted for oscillation in suitable bearings 25 rising from the carriage 1. The shaft 24 is oscillated by means of a crank arm 26, secured to one end of shaft 24, which arm is oscillated by a reciprocating link 27, having a lost motion connection with the revolving crank 31 of a speed-reducing mechanism 33. The lost motion is accomplished by providing the link 27, with a slot 30, Fig. 45 2, carrying a slidable block in which is journaled the pin 29, carried by crank 31, of the speed reducer 33. The shaft 32 of speed reducing mechanism 33 is driven by an electric motor 34, all of the parts referred 50 to being mounted upon and supported by the carriage 1, as more clearly shown in the drawings. The electric motor 34, is controlled by a suitable controller from a remotely located control station so that an operator by pressing a button or closing a 55 switch may control the operation of the motor and the tilting of the ladle. The motor 34, is provided with any well known type of control for obtaining various speeds to 60 control the speed at which the ladle for the molten metal is tilted.

The shaft 32, of the speed reducer 33, rotates to cause the crank 31, to make complete revolutions, whereas the crank 26, 65 mounted upon the shaft 24, is arranged to

oscillate only, and thus cause a back and forth movement of the crank 26, to move the ladle 21 to a completely tilted position and then reversely to its normal position of rest as shown in Fig. 1.

The crank arm 31 carried by shaft 32 is shorter than the crank arm 26 so that one complete revolution of shaft 32, with its crank arm 31 operates to give a full tilt of 90 degrees or approximately 90 degrees to 70 the ladle. The degree of tilt may be regulated by proportioning the length of the operating levers. When the crank 31, is in the position shown in Fig. 2, which represents 75 180 degrees travel from the position of the crank shown in Fig. 1, or a full stroke of the same, the ladle 21 will assume the extreme pouring position shown in Fig. 2. In other words, a one-half revolution of 80 crank arm 31, describes a rotary motion of 90 degrees and continued rotation of crank 31, through 180 degrees of a circle, returns 85 the ladle 21 to its original position for re-filling with the molten metal.

The connecting rod 27 is provided with a 90 lost motion connection 29, with the crank 31, in order to provide a clearance between the parts to avoid jamming and shocks when the ladle is returned to normal position from its tilted position. In other words if, during 95 the return movement of the ladle from tilted to normal position, any foreign material should become lodged under the seat of the ladle bracket to prevent the ladle from coming back to rest in its true position, the lost motion connection between the pivot point 29, of the rod 27, and the slot 30 will come into play, and thus prevent any jamming of the parts which might result in breakage thereof. Furthermore, it will be understood 100 that lengthening or shortening of the slot 30, to give more or less lost motion also determines the point at which the ladle begins 105 its tilting motion. This provides another means for varying the time required 110 for tilting or pouring the molten metal from the ladle into the hopper 19, and from thence into the pouring spout or trough 14.

In order to provide a balance for the ladle and assist the motor in tilting the same, we provide the oscillating shaft 24, with a pair of upwardly and forwardly inclined arms 35, each carrying one or more removable counterweights 36, which may be held in position on the arms by means of screws 37. These counterweights serve to balance the ladle, and the molten iron therein to relieve the motor and thus permit more accurate speed regulation thereof. The number of counterweights employed will vary according to the amount of metal in the ladle, it being understood that in practice the ladle is supplied with only sufficient metal to make a single cast.

The electric motor 8, for driving carriage

1 may be of such a type that the carriage 5 may be driven either forward or backward to move the pouring spout 14 into the flask A and to remove the same therefrom, or the motor may be of such a type as to move the carriage 1 in one direction only, in which event the carriage may be moved in the other direction manually. The operation of the mechanism is as follows:

- 10 Assuming the carriage to be in the position shown in Fig. 1 it will be seen that the discharge end 15, of the trough is located well within the flask A, so as to discharge the molten metal substantially midway between the ends of the flask. In this position the front wheels 2, of the carriage are resting against the stops or bumpers 4, which determine the forward position of the carriage and its trough. The bumpers may, if desired, be adjusted longitudinally of the tracks to regulate or change the distance at which the free end of the trough enters the flask. The ladle 21 is supplied with a predetermined amount of metal, which is 25 weighed when the carriage is resting upon the track sections 5, supported by the scale platform to the left of Fig. 1. The carriage is then moved to the position shown in Fig. 1, the motors 8 and 34 are then started by 30 the remote control switches so that the carriage with its trough 14 begins to move rearwardly gradually withdrawing the trough from the flask and at the same time the ladle 21, is tilted as the carriage is retracted to 35 discharge its molten metal into the hopper 19 and thence into the trough 14, and then through the outlet 15 into the flask A, it being understood that the flask is rotating at a high speed during the discharge of the 40 metal therein from the trough. By this arrangement the metal is distributed uniformly throughout the length of the flask, the distribution being aided by centrifugal force.
- 45 When the carriage has been moved to completely withdraw the trough from the flask, it is then positioned on the platform scales to receive a new charge of molten metal, and the cycle of operation is repeated. It is obvious that the metal may be poured on either 50 the forward or backward movement of the carriage, although we prefer to pour the metal while the trough is being withdrawn from the flask.
- 55 As hereinbefore stated I prefer to control the movements of the carriage 1 and the tilting of the ladle 21 from a remote station at which a switchboard of suitable construction may be located and having controls for several carriages if desired.

In Fig. 1 I have shown in a more or less diagrammatic and conventional fashion one set of remote controls and their circuits leading to the electric motor 8 for driving the 60 carriage and the electric motor 34 for tilt-

ing the ladle, it being understood that any known construction of control mechanism, of which several may now be procured upon the open market, may be employed. In such controls it is usual to provide push buttons or other forms of switches for controlling the circuits to the motors. In the conventional showing the panel 40 carries three push-buttons switches for causing the electric carriage-driving motor to operate to 70 drive the carriage either forward or backward and to stop its movement at will, while the panel 41 carries two push button switch controls by which the motor 34 may be started and stopped at will to tilt the ladle 21. 75

While we have illustrated and described a preferred embodiment of our invention we do not wish to be understood as limiting ourselves to the structures shown except as we may be limited to the terms of the appended 80 claims.

What we claim is:

1. Charging mechanism for centrifugal casting machines, including a tilting ladle, a 90 rock shaft to which the ladle is secured, a crank arm on said shaft, and means for rocking said shaft, comprising a motor-driven speed-reducer having a crank-shaft adapted to make complete revolutions in one direction and a link-connection between the said crank-arm and crank-shaft operable during each complete revolution of the crank-shaft to impart a rocking movement to the rock-shaft to tilt and then restore the ladle to 95 normal position. 100

2. Charging mechanism for centrifugal casting machines, including a tilting ladle, a rock shaft to which the ladle is secured, a crank-arm on said shaft, and means for 105 rocking the shaft comprising a motor-driven speed-reducer having a crank-shaft adapted to make complete revolutions in one direction, and a link having a lost-motion connection between the said crank-arm and the crank-shaft operable during each complete revolution of the crank shaft to impart a 110 rocking movement to the rock shaft to tilt and then restore the ladle to normal position.

3. Charging mechanism of the class described, including a tilting ladle, a rock shaft to which the mouth portion of the ladle is directly secured and about which it tilts as an axis, an upwardly-inclined arm secured to said shaft, a counter-weight carried by said arm and normally influencing tilting movement of the ladle to pouring position, a crank-arm also secured to the rock shaft, and means for rocking the shaft comprising a motor-driven speed-reducer having a crank shaft adapted to make complete revolutions in one direction and a link connection between the said crank-arm and crank-shaft operable during each complete 115 revolution of the crank-shaft to impart a 120

125

rocking movement to the rock shaft to tilt and then restore the ladle to normal position.

4. Charging mechanism for centrifugal casting machines comprising a wheeled carriage and an electric motor mounted thereon for moving the carriage, a charging spout carried by and projecting from one end of the carriage, a tiltable ladle mounted upon the carriage and arranged to discharge molten metal into the spout, a rock-shaft to which the ladle is directly secured and about which it tilts as an axis a crank-arm on said shaft, and means for rocking the shaft comprising a motor-driven speed-reducer having a crank-shaft adapted to make complete revolutions in one direction and a link connection between the said crank-arm and crank-shaft operable during each complete revolution of the crank-shaft to impart a rocking movement to the rock-shaft to tilt and then restore the ladle to normal position.

5. Charging mechanism for centrifugal casting machines comprising a wheeled carriage, a motor thereon for driving the same, a tiltable ladle mounted upon the carriage, an oscillating shaft to which the ladle is directly attached at its pouring mouth and about which it tilts as an axis said shaft having a crank-arm and a pair of upwardly-extending inclined arms, each carrying a counter-weight normally influencing the tilting movement of the ladle, and means for rocking said shaft comprising a motor-driven speed-reducer having a crank-shaft adapted to make complete revolutions in one direction, and a link connection between the said crank-arm and crank-shaft operable during each complete revolution of the crank-shaft to impart a rocking movement to the rock-shaft to tilt and then restore the ladle to normal position, said motor-driven speed-reducer being mounted upon the carriage at one side of the ladle.

Signed at Birmingham in the county of Jefferson and State of Alabama this 17th day of September A. D. 1931.
